US00D904820S

(12) **United States Design Patent** (10) Patent No.: **US D904,820 S**
(45) Date of Patent: **** Dec. 15, 2020**

(54) **OVEN**

(71) Applicant: **LG ELECTRONICS INC.**, Seoul
(KR)

(72) Inventors: **Sooyeon Kim**, Seoul (KR); **Hongsik Kwon**, Seoul (KR); **Suhyeon Son**, Seoul (KR); **Inhwan Ryu**, Seoul (KR); **Songyi Han**, Seoul (KR)

(73) Assignee: **LG ELECTRONICS INC.**, Seoul
(KR)

(**) Term: **15 Years**

(21) Appl. No.: **35/508,026**

(22) Filed: **Jun. 4, 2019**

(80) **Hague Agreement Data**

Int. Filing Date: **Jun. 4, 2019**

Int. Reg. No.: **DM/204071**

Int. Reg. Date: **Jun. 4, 2019**

Int. Reg. Pub. Date: **Dec. 6, 2019**

(51) **LOC (12) Cl.** **07-02**

(52) **U.S. Cl.**

USPC **D7/349**

(58) **Field of Classification Search**
